OIL SEPARATOR FOR REFRIGERATION SYSTEMS

George W. Smith and James A. Smith, Lyons, N. Y., assignors to Kenmore Machine Products, Inc., Lyons, N. Y.

Application March 9, 1939, Serial No. 260,711

5 Claims. (CL. 62—115)

This invention relates to an oil separating device which is adapted for use in refrigeration systems.

In large refrigeration systems it has been proposed to cause the separation of oil from the compressed gas while the refrigerant is still in the vapor phase, that is before it is subjected to condensation, the objective being to eliminate all oil from the evaporative portions of the system and thus to obtain an increased effectiveness. The practical solution of this problem has proved troublesome, not only from a mechanical viewpoint, but also for thermal reasons, since secondary condensation of refrigerant in the separator induces the risk of the return of liquid refrigerant to the compressor.

In the present invention there is provided a simple and effective separating device which contains a novel regenerative heating arrangement, by which means the accumulation of liquid refrigerant is entirely prevented. The operation of this separator is wholly automatic in its oil return and heating functions, and it performs these duties without imposing any discernible additional load on the system.

The more specific aspects of the invention will be more apparent from a study of the accompanying specification and drawing, wherein:

Fig. 1 is a vertical section through the separator showing in addition a diagrammatic layout of an associated refrigeration system;

Fig. 2 is an enlarged fragmentary section on the line 2—2 of Fig. 1, with the float and valve needle shown in elevation;

Fig. 3 is a section on the line 3—3 of Fig. 2; and

Fig. 4 is a perspective view of the fusible alloy ring insert.

As shown in Fig. 1, the separator may be interposed in that portion of a refrigeration circuit connecting the compressor 10 and the condenser 11. The separator includes a cylindrical housing 13 capped by upper and lower heads 14 and 15 respectively, the former head carrying inlet and outlet fittings 16 and 17 connected to the outlet of the compressor and to the condenser respectively by pipes 18 and 19. An oil return fitting 20 is carried low in the wall of the housing 13, and a pipe 21 which is connected thereto carries separated oil volumes back to a crankcase fitting 23 on the compressor 10. Studs 24 are secured to the lower head 15 and they serve to mount the unit on a suitable base B, as indicated in dotted lines in Fig. 1.

A slotted sleeve 25 is secured to the inner end 16a of the fitting 16, and the sleeve carries a filter

mass 26 which is retained therein by a cotter pin 27. A perforate washer 27a may be interposed between the pin and filter mass 26. The outlet fitting 17 is formed with a comparatively longer end or barrel 17a, which end contains a bore 32 adapted to receive slidably one terminal 28a of a heating coil 28. The coil is formed with a circular section 29 which rests on the lower head 15, and the remaining terminal 28b of the coil extends vertically along the wall of the housing 13 to a high point adjacent the upper head 14.

The oil return fitting 20 is a two-part structure (Fig. 2) consisting of a valve body 30 and a shouldered pipe bushing 31, which bushing enters through a hole 33 in the housing and is pressed into a bore 34 in the body 30. The body 30 contains a vertical passage 36 having a tightly fitted seat insert 37 at its upper end, with the remainder of the passage serving as a guide chamber for a valve needle 38. A transverse drilled hole 40 in the body establishes communication between the valve seat and the pipe bushing 31, while a second hole 41 connects the valve passage 36 to the interior of the housing.

The valve needle 38 is operated by a float-controlled mechanism including a float lever 43, one end of which is received within the bifurcated lower extremity 44 of the valve body. A pivot pin 45 extends transversely through suitable holes in the bifurcations and lever, and it is retained against displacement by a spring clip 46, whose beaded sides 47 anchor over the projecting ends of the pin (Fig. 3). A vertical hole 48 in the lever receives loosely the projecting lower end of the valve needle 38. A pin 49 extends transversely through lever and needle to provide a pivotal assembly. A hollow float 50 is provided with a depending stud 51 which enters a vertical clearance hole 52 in the free end of the lever. A transverse pin 53 provides an assembly similar to that of the valve needle connection.

It will now be apparent that oil accumulating in the lower end of the separator will cause the float-controlled opening movement of the valve needle, and the corresponding effluence of oil through the seat 37 and thence through the pipe 21 back to the crankcase of the compressor. In its raised or open position, the extreme left hand portion of the lever 43 engages a stop pin 55 to limit further movement.

It is preferred that the housing 13 and upper head 14, together with the fittings thereon, be united by hydrogen welding to form a substantially integral structure, into which the float mechanism, heating coil, and filter pack are later

inserted in their proper operative positions. The unit is finally sealed by applying and welding the lower head 15. During the hydrogen welding process it will be observed that the compound joint structure of the oil return fitting 20 is supplied with a ring 57 of a fusible alloy, as shown in Fig. 4, which ring is inserted in the bore 34 of the body 30. When suitable heat is applied, the ring 57 melts, and, by capillary flow action, seals not only the pipe bushing 31 to the body 30, but flows about the edges of the housing hole 33 and thus firmly secures both parts of the fitting to the housing.

In the operation of the separator, the relatively hot compressed gas delivered by the compressor through the pipe 18 impinges directly upon the filter mass 26 before escaping into the upper portions of the housing 13. Such impingement encourages the coalescence of oil particles which have been entrained with the refrigerant gases in the compressor 10, and accordingly the oil drips through the perforate washer 27a and gathers in a liquid body O in the bottom of the housing. The separated gas, in the meantime, enters the terminal 28b of the heating coil and finally is directed to the condenser through the outlet fitting 17 and pipe 19.

It will be appreciated, since the compressor 10 is only intermittently operated in response to load demands of the system, that the compressed refrigerant gas within the separator will be subject to condensation during the periods in which the compressor is inactive. As a result, small quantities of liquid refrigerant gather in the oil body O, and such bodies if returned with the oil during subsequent cycles, create a serious hazard to the mechanism of the compressor, as is well known in the art. This possibility is avoided through the effect of the heating coil 28, which, during the subsequent cycle, receives the entire hot gas discharge of the compressor. The immersed portions of the coil thus immediately affect the temperature of the now relatively cold oil body, and the included liquid refrigerant volumes are rapidly evaporated and driven off. It will be understood that the liquid refrigerant will sink in the oil, and thus any oil return action occurring prior to heating will not create a serious problem, since the valve outlet hole 41 is at a relatively high level.

While the invention has been described with respect to a single embodiment, it will of course be understood that it is susceptible of modifications and variations such as are encompassed by the scope of the following claims.

We claim:

1. An oil return device comprising a housing having a refrigerant gas inlet and outlet, a passage within said housing having one terminal communicating with a high point within said

housing, a body portion extending to the bottom of the housing, and its remaining terminal communicating with said outlet, a float controlled valve mechanism including a valve seat disposed within the housing adjacent the bottom thereof, and an oil return conduit communicating with said valve seat.

2. An oil return device comprising a housing having a refrigerant gas inlet and outlet, a tubular heating coil disposed within said housing and having one terminal communicating with a high point within the housing, a bent body portion extending to the bottom of the housing, and its remaining terminal communicating with said outlet, a float controlled valve mechanism including a valve seat disposed within the housing adjacent the bottom thereof, and an oil return conduit communicating with the valve seat.

3. An oil return device comprising a housing having a refrigerant gas inlet and outlet, said inlet being located adjacent the top of the housing and having an extension within said housing containing a foraminous mass to provide an oil and gas dividing means, said outlet having a tubular extension depending to the bottom of the housing and having a terminal extending vertically to a high point in the housing, a float controlled valve mechanism including a valve seat disposed within the housing adjacent the bottom thereof, and an oil return conduit communicating with said valve seat.

4. An oil return device comprising a housing having a refrigerant gas inlet and outlet, a valve fitting secured within the housing adjacent the bottom thereof and containing a vertical valve guide passage terminating in a seat portion, an oil return conduit secured to the exterior of the housing and communicating with said seat, a valve in said guide passage, a lever pivotally carried on the fitting and having an opening therein for loosely receiving the end of said valve, a pin extending through the lever and valve to provide a pivotal mounting for the valve, and a float connected to said lever.

5. An oil return device comprising a cylindrical housing having securing means at one extremity for mounting the housing on a vertical axis, inlet and outlet fittings disposed in the opposite extremity of the housing, a tubular heating coil disposed within the housing and having one terminal communicating with a high point within the housing, a body portion extending to the bottom of the housing, and its remaining terminal slidably entered in said outlet fitting, a float controlled valve mechanism including a valve seat disposed within the housing adjacent the bottom thereof, and an oil return conduit communicating with the valve seat.
